UNITED STATES PATENT OFFICE.

WILLIAM H. DIETZ, OF CHICAGO, ILLINOIS.

BULLETIN-BOARD.

1,203,712.

Specification of Letters Patent. Patented Nov. 7, 1916.

Application filed February 12, 1914. Serial No. 818,201.

To all whom it may concern:

Be it known that I, WILLIAM H. DIETZ, a citizen of the United States, and a resident of Chicago, in the county of Cook and State 5 of Illinois, have invented certain new and useful Improvements in Bulletin-Boards; and I do hereby declare that the following is a full, clear, and exact description thereof, reference being had to the accompanying 10 drawings, and to the letters of reference marked thereon, which form a part of this specification.

This invention relates to improvements in bulletin boards and consists of the matters 15 hereinafter described and more particularly pointed out in the appended claims.

The object of the invention is to produce a simple and efficient bulletin board with which is provided a plurality of slips or 20 cards, each card having a letter or numeral or the like thereon, there being means on said bulletin board for holding the cards in proper position, so that they will spell certain words or phrases or indicate time or 25 price in numerals, such as the case may be.

The object furthermore relates to the manner in which the certain word or phrase forming cards are supported or held by means of holding strips upon the panel. 30 Said holding strips are so made that the cards may be inserted or placed thereinto from the front thereof into their proper places eliminating the necessity of inserting said cards into position between said strip 35 from the ends thereof and moving the same edgewise therealong to their proper positions between said strips.

In the drawings: Figure 1 is a view in perspective of my improved bulletin-board, 40 showing the same as attached to a wall, with the parts in a position permitting the removal of the card holding panel. Fig. 2 is a vertical section through the same on a slightly larger scale, with the parts in the 45 position they assume when the card holding panel is locked in place. Fig. 3 is a detail horizontal sectional view on an enlarged scale, the plane of said section being indicated by line 3-3 of Fig. 1. Fig. 4 is a detail perspective view of a part of the panel board and its associated card holding strips, with an end card and an adjacent card held in position thereon by means of said strips. 50 Fig. 5 is a diagrammatic vertical sectional view through the panel and a pair of card 55

holding strips illustrating the manner in which the cards are placed in said strips to be held in position thereby.

Referring more in detail to that embodiment of my invention illustrated in the accompanying drawings, 10 indicates a rectangular frame which may be attached to and preferably spaced from a supporting wall 11, by means of clips 12. Said frame comprises horizontal top and bottom members 13, 13 and vertical end members 14, 14, joined at their intersections in a suitable manner. To said frame members is secured a backing plate 15 of sheet metal or other suitable material. Said frame members 13 60 and 14 are rabbeted as at 16 (see Figs. 2 and 3) to form a seat for a supplemental panel bearing frame 17.

18 indicates a cover frame which is hinged to the upper rear edge of the frame 10 by 70 means of hinges 19. Said frame 18 comprises horizontal upper and lower members 20 and vertical end members 21. Said members are provided with metal facing strips 22 and said facing strips are formed with 80 flanges 23, 23 which project over and inclose the members 13 and 14 of the frame 10, when said frames are in a closed position as indicated in Figs. 2 and 3 respectively, in this manner making the bulletin board water- 85 proof. The two frames are locked together when in this position by means of a hinged hasp 24, one member of which is fixed to the lower horizontal member 13 of the frame 10, and through the other member of which a 90 coacting eye 25 formed on the hinged frame 18 projects, a padlock 26 being used in locking the same in this position (see Fig. 2). Said frame 18 is provided with a pane of glass 27 held therein in a suitable manner, through 95 which the matter depicted upon the supplemental panel frame 17 may be observed.

The supplemental frame 17 comprises rabbeted horizontal upper and lower frame members 28, 28 and vertical end members 29, 29, and seated in the rabbeted portions of said members and attached thereto is a panel board 30 made preferably of a heavy sheet of water proof paper. To said panel are attached horizontally extending spaced strips 100 31 which coact with one another for the reception and holding of a plurality of numbered or lettered cards 32 in the following manner.

Each strip is made in the form of a rail 110

having a base or body 23 which engages with and is fixed to the panel board 30 in a suitable manner. Made integral with and in a plane parallel with but spaced from the base 5 or body 23 are upper and lower flanges 34, 35, which are connected to the said base 23 by outwardly extending top and bottom web portions 36, 36^a. The lower flange 35 is of a vertical width greater than that of the 10 flange 34 and being the lowermost flange of the strip, said flange retains or holds the upper edge of each card 32 supported by the strip below.

Each card is of a height greater than the 15 distance between the web 36 of one strip and the lower edge of the flange 35 on the adjacent strip vertically above it, consequently when in placing the cards in between the strips, should the lower edge of the card 20 be first inserted so as to rest on the web 36 of one of said strips, the upper edge of said card would project upward beyond the lower edge of the flange 35 on the adjacent strip above. Thus the card could not be inserted 25 between said flanges in this manner. This position is shown in the upper end of Fig. 5. On the other hand, the distance between the web 36^a of one strip and the upper edge of the flange 34 on the adjacent strip vertically 30 below it is greater than the height of each card 32, and to place the card between said strips, the upper end of said card must be first inserted under the lower flange 35 of one of the strips 31 until the upper edge of said 35 card abuts against the web 36^a of said strip. The lower edge of said card will then be slightly above the upper edge of the flange 34 of the adjacent strip below (see lower part of Fig. 5) when said card may be 40 moved inwardly against the panel 32 and then moved downwardly until the lower edge thereof rests on the web 36. The card 32 then cannot fall out from between the flanges 35, 34, respectively, for the reason 45 that the upper edge of the card now projects above the plane of the inner lower edge of the flange 35. In this manner, the cards may be inserted in their proper place from the front of the panel, thus eliminating the 50 necessity of inserting said cards at the ends of said strips as has been heretofore done, this requiring the sliding the cards between the flanges of the coacting strips. To remove said cards, the same are moved upwardly so that the lower edge of each card 55 is in a plane above the plane of the upper edge of the flange 34 when they may then be easily removed without moving said cards edgewise toward the ends of the strips. Said 60 cards 32 are not as thick as the space between the flanges 34, 35 and the panel board 30, and are made in that form so that they may be easily handled and inserted into their proper places.

65 Cards without printed matter thereupon

may be used for spaces between the various words or numbers and such a card is indicated at 39 in Fig. 1.

I might find it desirable to provide several cards of a thickness equal to the space between the panel and the flanges 34, 35, as indicated at 40 in Fig. 4, such card to be used only at the end of a row of cards. Said cards 40 will prevent endwise separation between the cards 32 of a certain row.

When the said panel board 30 with its card holding strips and the various cards is in position within the frames 10 and 18, the front faces of the various strips will be approximately flush with the front face of 70 the members 13 and 14 of the frame 10, and when the hinged frame 18 is in closed position as indicated in Figs. 2 and 3, the inner lateral edges of the various frame members 20 and 21 will overlap a portion of the lateral edges of the panel frame 17 and securely hold the same in position.

When it is desired to present new matter to the observer, by means of inserting new cards or changing position of the cards already therein to spell new words or phrases, the padlock 26 is unlocked and removed, and the hasp member 24 swung downwardly about its point of pivot, away from the eye 25, when the frame 18 may be swung upwardly about the hinges 19. Said frame 18 may then be held in the desired open position, as indicated in Fig. 1, by means of a hook 37 which is pivoted at one end to one of the side members 21 of the frame 18 and 90 which co-acts at its other end with an eye 38 fixed to the frame 10. The member 23 of the frame 18 is notched out to permit said hinged frame 18 to close without being interfered with by the eye 38. When not in 105 bracing position, the hook 37 is adapted to lie in a plane adjacent to the member 23 of the frame 18. When the parts are in this position, the supplemental frame 17 with its panel and strips and the cards held therein 110 may be withdrawn from the frame 10 so that the same be rested on a suitable horizontal support such as a table, etc., and the cards may then be changed as desired.

A sign made in accordance with my invention is waterproof. The panel is easily removable to permit insertion of new cards thereinto or the withdrawal of certain cards already therein from their places between the holding strips as before described, thus 115 eliminating the moving of the entire plurality of cards edgewise one by one to either end of the strips to permit of removal in this manner therefrom.

This manner of inserting and removing 120 of certain cards saves time and annoyance, as mistakes in spelling may be easily rectified without removing all the cards in a set.

While I have described certain details of construction, I do not wish to be limited 125

thereby except as pointed out in the appended claim.

What I claim is:—

A bulletin board, comprising a closed back frame, a secondary frame adapted to close upon the first named frame and having a transparent face, said back frame comprising rabbeted upper and lower and end frame members, a supplemental frame removably engaged in the rabbeted part of said back frame, said supplemental frame including a backing member, vertically spaced horizontal retaining strips fixed on said backing member, card members adapted to be retained by said strips, each strip comprising a base attached to the backing member and top and bottom flanges spaced from said base, the top flange being of less depth than the lower flange and the vertically adjacent

strips being spaced apart at a distance to 20 permit the insertion of the card members between them, the front faces of the supplemental frame and of its card retaining strips being in the same plane as that of the front face of the back frame and said secondary frame being adapted to engage and overlap the lateral edges of said supplemental frame when the secondary frame is in closed position and means for locking said secondary frame in said closed position. 25 30

In testimony, that I, claim the foregoing as my invention I affix my signature in the presence of two witnesses, this 7th day of February, A. D. 1914.

WILLIAM H. DIETZ.
